UNITED STATES PATENT OFFICE.

WILLIAM H. THOEMING, OF DETROIT, MICHIGAN, ASSIGNOR TO VANGUARD MANUFACTURING COMPANY, OF HAMTRAMCK, MICHIGAN, A CORPORATION OF MICHIGAN.

WIND-SHIELD.

1,123,150.

Specification of Letters Patent. Patented Dec. 29, 1914.

Application filed March 9, 1914. Serial No. 823,512.

To all whom it may concern:

Be it known that I, WILLIAM H. THOEMING, a citizen of the United States of America, residing at Detroit, in the county of Wayne and State of Michigan, have invented certain new and useful Improvements in Wind-Shields, of which the following is a specification, reference being had therein to the accompanying drawings.

10 The invention relates to wind-shields and has more particular reference to the construction of the supporting frame and the means employed for forming a pivotal connection between said frame and the wind-shield sections, the invention comprising various features of construction as herein-after set forth.

In the drawings: Figure 1 is a front elevation of a portion of the shield partly in section; Fig. 2 is an elevation looking at right angles to Fig. 1, and showing one section of the shield removed; Fig. 3 is an elevation of the removed section; and Fig. 4 is a cross section in the plane of the pivot.

25 A and B are the frames for the glass panels of the shield, which are formed as usual of tubular members channelled along their inner edges for the reception of the glass.

30 C are threaded studs having threaded engagement with suitable filler members or the like in the tubular frames A and B. E are disks or face plates. These are preferably formed of sheet metal stampings, fashioned with a central segmental portion E' fitting 35 the curvature of the tube and having wing portions E² on opposite sides of said central portion and in the same plane.

F is a reinforcing disk secured to the disk E by round-head rivets G, which perform 40 the further function of locking detents as hereinafter described.

H is the stationary frame for supporting the swinging sections A and B. This is 45 preferably formed of a channel member having enlargements H' at the points where the pivots or centers for the frames A and B are located. The member H is preferably formed from a sheet metal blank, bent into channel section and having the portions 50 forming the enlargements H' drawn into a hemispherical form.

I is a member fitting within the channel of the member G and having enlarged heads I' at its opposite ends, which fit within the 55 enlargements H' and form bearing plates

adjacent to the disks E and F. These enlarged heads I' are centrally apertured for the passage of the studs C, and surrounding and concentric with this aperture is a series of notches or depressions J for engagement 60 with the detents formed by the rivet heads G. The heads I' are yieldably and resiliently pressed against the detents G by springs K surrounding the studs C. These springs are preferably tensioned by abut- 65 ting against nuts L on the studs, which are locked by suitable means such as the cross pins L'. The studs C extend outward a sufficient distance to pass through apertures in the enlargements H', being shouldered at 70 C' for bearing against the inner face of the frame member and being clamped thereto by nuts M engaging projecting threaded ends.

With the construction as described the 75 hinged sections A and B, together with the pivot centers formed by the members E F G I K L, may be assembled as a unit independent of the stationary frame H. This unit may then be attached to the frame 80 merely by inserting the end of the studs C through the apertures in the enlargements H' and securing by engagement of the clamping nuts M. When thus mounted, the member I, which lies within the channel 85 of the frame member H, forms in effect an integral portion thereof and an anchor plate for the centers of the frames A and B. These frames may then be adjusted to different angles, as the resiliency of the spring K 90 will permit the detents G to be disengaged from the notches J. At the same time the tension of the spring will hold the detents in engagement with said notches so as to prevent accidental turning of the frames. 95

It will be observed that the member I performs the function of a tie member between the studs C forming the respective centers of the frames A and B. This member also anchors the heads I' from rotation and further forms a lining or closure for the channel in the member H.

The frame members H are preferably formed at their lower ends with their side flanges laterally extended as at H², and curved to conform to the curvature of the frame B. These members may then be secured to the vehicle either by embracing the dash N or by mounting in any other suitable way.

What I claim as my invention is,—

1. In a wind-shield, a plurality of independently swinging frames, a unit mounting for said frames, and a supporting stationary frame having a recess to receive and adapted to detachably engage said unit mounting.
2. In a wind-shield, the combination with a swinging tubular frame, of a pivot center 10 therefor, comprising a filler member within the tubular frame, a stud engaging said filler member and projecting outward from said tubular frame, coöoperating detent-engaging members sleeved upon said stud, and a recessed supporting frame member independent of and embracing said detent-engaging members and secured to the end of said stud.
3. In a wind-shield, the combination with a swinging tubular frame member, of a 20 filler-block within the section of the tubular frame member, a stud engaging said filler-block and projecting outward from said tubular frame member, coöoperating spring-pressed detent-engaging disks sleeved upon said stud, and a recessed frame member independent of and adapted to inclose said stud and members mounted thereon.
4. In a wind-shield, the combination with a swinging tubular frame member, of a 30 filler-block within the section of the tubular frame member, a stud engaging said block and projecting outward, a disk sleeved on said stud, fashioned to embrace said tubular frame member and to be held from rotation thereby, a relatively-rotatable disk adjacent to said first-mentioned disk, a detent on one of said disks engaging a series of notches on the adjacent disk, a spring sleeved upon said stud for yieldably pressing said disks 35 together, and a recessed supporting frame member for receiving said spring stud and disks and having an anchoring engagement with said relatively-rotating disk.
5. In a wind-shield, the combination with 45 a swinging frame, of a stud secured to and projecting outward from said frame, a disk fashioned with a segmental portion embracing said frame and sleeved upon said stud, an adjacent flat disk, a rivet for securing said disks together having a projecting head forming a detent, a disk sleeved upon said stud notched for engagement with said de-

tent, a spring upon said stud for yieldably pressing the last-mentioned disk to engage said detent, and a recessed supporting frame 55 member for receiving the parts mounted on said stud and having clamping engagement with the latter.

6. In a wind-shield, the combination with channeled frame member, of a plurality of 60 swinging frames, a pivot center for each frame secured to said channeled frame member, and a connecting bar having its opposite ends forming corresponding elements of said pivot centers, entering the channel of 65 said stationary frame member.

7. In a wind-shield, the combination with a channeled stationary frame member, of a plurality of swinging frames, a pivot center for each of said frames having a projecting 70 stud, a connecting bar having its opposite ends forming corresponding elements of said pivot centers, entering the channel of said stationary frame member, and clamping means on said studs for securing the same to 75 said stationary frame member.

8. In a wind-shield, the combination with the stationary frame member having enlargements at separated points, of a plurality of swinging frames each provided 80 with a pivot center for respectively engaging said enlargements in said stationary frame, and a connecting bar fitting within the channel of said stationary frame, having its opposite ends forming corresponding elements 85 of said pivot centers.

9. In a wind-shield, the combination with a plurality of independently-swinging frames, of a pivot center for each frame, a connecting bar between said pivot centers 90 having its opposite ends enlarged and forming corresponding elements of said centers, and a stationary channel frame member having separated enlargements for receiving said centers and the ends of said connecting bar, the intermediate portion of said bar extending within the channel. 95

In testimony whereof I affix my signature in presence of two witnesses.

WILLIAM H. THOEMING.
